United States Patent Office

Des. 193,957
Patented Oct. 30, 1962

193,957

GARBAGE CAN HOLDER

Marion Young, 1624 W. 23rd, Little Rock, Ark.

Filed Oct. 30, 1961, Ser. No. 67,295

Term of patents 14 years

(Cl. D58—26)

FIG. 1

FIG. 2

FIGURE 1 is a perspective view of a garbage can holder showing my new design; and

FIGURE 2 is a top plan view thereof.

I claim:

The ornamental design of a garbage can holder, as shown.

References Cited in the file of this patent

UNITED STATES PATENTS

1,779,867	Ahrold	Oct. 28, 1930
2,739,466	Maliniak	Mar. 27, 1956